HOUSING FOR ELECTRONIC EQUIPMENT

Leon Gordon Miller, Shaker Heights, Ohio, assignor to
Bud Radio, Incorporated, Willoughby, Ohio

Filed Aug. 28, 1970, Ser. No. 24,748

Term of patent 14 years

Int. Cl. D14—02

U.S. Cl. D26—5

FIG.1

FIG.2

FIG. 1 is a perspective view of a housing for electronic equipment embodying my new design showing the front, top and one side thereof; and

FIG. 2 is a perspective view of the housing for electronic equipment embodying my new design showing the rear, bottom and the side opposite to the side shown in FIG. 1.

I claim:

The ornamental design for a housing for electronic equipment, as shown and described.
